ADJUSTABLE HEAD T SQUARE

Oscar Anton Olson, Ames, Iowa

Application December 1, 1949, Serial No. 130,377

3 Claims. (Cl. 33—100)

1

My invention relates to an adjustable head T-square commonly used on rectangular drafting boards.

When using a T-square on a drafting board it is often desirable and necessary to produce lines at an angle to any one side of the board. This is frequently done by using a triangle in combination with the T-square, but such a method is limited to the angle which may be produced and to the relative short length of the triangle. These problems have heretofore been overcome by the use of a T-square with an adjustable head whereby the rule may be fixed at any desired angle to any side of the board and the length of the line that can be drawn is limited only by the length of the rule which generally is sufficient for most all work. In my invention, however, I have provided a new and more efficient means for adjusting the head on such a T-square.

It is, therefore, an object of my invention to provide a T-square that can be more accurately and quickly adjusted on a drawing board at any angle to any side thereof by providing it with a control means on the edge of the cross-piece head portion for efficiently adjustably securing one of the cross-head pieces in any desired set position.

A further object of this invention is to provide a T-square of the above character that has a pair of calibrated complementary cross-pieces pivotally secured together with a rule rigidly secured to one of them and a control means capable of engaging one edge of each of the cross-pieces to control the rotation thereof.

A still further object of this invention is to provide a T-square that is designed to eliminate ink from a drafting instrument adhering thereto and thereby causing smudge on the drawing.

A still further object of my invention is to provide a T-square of the above classes that is economical in manufacture and efficient and durable in use.

These and other objects will be apparent to those skilled in the art.

My invention consists in the construction, arrangement, and combination of the various parts of the device, whereby the objects contemplated are attained as hereinafter more fully set forth, pointed out in my claims, and illustrated in the accompanying drawings, in which:

Fig. 1 is a top plan view of my T-square showing one of the movable cross-pieces positioned at an angle to the longitudinal axis of the rule.

Fig. 2 is a view of the device in inverted position from that shown in Fig. 1 and shown positioned on a drawing board.

2

Fig. 3 is a cross-sectional view of the rule on this T-square taken on the line 3—3 of Fig. 2 with dotted lines showing the position of a drafting instrument using one side of the rule as a guide, and

Fig. 4 is a cross-sectional view of this device taken on the line 4—4 of Fig. 1.

Referring to the drawings I have used the numeral 10 to designate a common drafting board showing a sheet 11 for drawing affixed thereto. It is on such a board that my T-square is used. The numerals 12 and 13 respectively designate a pair of T-square cross-pieces or heads that are shaped in the usual form and with each having a beveled outside edge 26 on the central convex or arcular portion thereof, as shown in Fig. 1. These cross-pieces are each of the same size and shape and the top side of each is calibrated in degree so that the zero reading will be at right angles to the side that is designed to engage the periphery of the drawing board, as shown in Fig. 1.

An elongated rectangular, preferably translucent, rule member 14 is rigidly secured at one end to the top of the cross-piece 13 and at a right angle thereto by any suitable means such as the screws 15. As shown in Fig. 4 it should be noted that the rule is secured on only the inner top portion of the cross-piece 13 and terminates a distance from the outer arcular end of the cross-piece.

The cross-pieces 12 and 13 are pivotally secured together in spaced relation by the bolt 16 in such a manner that the cross-piece 12 can be rotated in a plane above and without interference from the rule 14. The bolt 16 is preferably of the type having a male and female portion so that it will tighten on itself to pivotally secure the cross-pieces 12 and 13 without binding the cross-pieces on the rule 14, as shown in Fig. 4.

In the cross-piece 13 just to the rear of the rule 14, I provide a well 17 to accommodate the hook portion 18 of the rod 19, as shown in Fig. 4. The thickness of the rod 19 should be such that it will fit in the space between the cross-pieces 12 and 13 and beyond the rule portion 14. A threaded portion 20 on the rod 19 projects forwardly and transversely beyond from convex portion of these cross-pieces, as shown in Fig. 4. This rod will be held in position by the cross-pieces 12 and 13 and can be removed only by removing the bolt 16, and its thickness is approximately that of the thickness of the rule 14.

The numeral 21 designates a substantially square channel shaped binding bracket that has

the inside of each channel edge beveled, as shown in Fig. 4. This bracket is designed to be mounted on the threaded portion 20 of the rod 19 so that the beveled portions respectively are capable of engaging the beveled edges 26 respectively on the convex portions of the cross-pieces 12 and 13, as shown in Fig. 4. A control nut knob comprising the finger grip portion 22 and rounded boss portion 23 is threaded onto the rod 19 and the rounded end of the boss portion can be tightened against the outside flat surface of the bracket 21.

The numeral 24 designates a beveled edge along one longitudinal side of the rule 14 and the numeral 25 designates a drafting instrument.

When this T-square is constructed and arranged as described it can be used in the following manner:

When the cross-piece 13 is placed in engagement with the side edge of a drawing board, this device provides an ordinary T-square. This is true because the rule 14 is secured to the cross-piece 13 and extends therefrom at right angles. However, whenever it is desired to place the rule 14 on the drawing sheet 11 at an angle to any side thereof, the control knob can be manually rotated counterclockwise to release the bracket 21 from engagement with the cross-pieces 12 and 13. This will permit the cross-piece 12 to be pivoted and by use of the calibration either on the piece 12 or 13, the piece 12 can be set at any desired angle of degree. When this has been determined the control knob is then tightened so that the channel bracket 21 frictionally engages the beveled edges on the cross-pieces 12 and 13 to hold the piece 12 at the selected position.

The T-square is then inverted and the cross-piece 12 is placed in engagement with the periphery of drawing board in the usual manner with the result that the rule 14 will now be at an angle corresponding to the degree to which the cross-piece 12 was pivoted. The above process can be repeated as often as lines at different angles are required and the control knob and bracket will function efficiently to securely hold the new setting each time.

The position of my control knob and bracket at the edge of the cross-pieces has several advantages over present type adjustable head T-squares that usually have curved slots through the cross-pieces with a bolt arranged transversely the slots for tightening the head at various positions. In my device the head of the T-square is more economical to construct since no slots are required. Secondly, since the cross-pieces are not slotted, the calibrations can be more plainly marked and are easier to read. Still another advantage of my T-square is that by arranging the control means at the edge of the cross-pieces they are more effectively secured in different positions than those devices having a control means transversely the center portions of the T-square heads.

The reason for this is that the bracket 21 wedges on to the bevels 26 of the heads thereby accurately bringing them together uniformly at all times in rigid clamped arrangement. The self-centering of all such parts for accuracy is brought about by the bevel edges 26, the inner complementary bevels of the bracket and the rounded end of the tightening nut that permits the bracket to evenly center itself onto the cross-pieces. By the knob 22 being on the end of my device it is in a most handy position, regardless of whether the rule is in inverted or upright position.

The beveled edge 24 on the rule 14 eliminates any contact between the rule and the drafting instrument 25 at the surface of the papers, as shown in Fig. 3. By this arrangement there is no danger of ink adhering to the rule and causing a smudge or blot on the drawing.

Some changes may be made in the construction and arrangement of my adjustable head T-square without departing from the real spirit and purpose of my invention, and it is my invention to cover by my claims, any modified forms of structure or use of mechanical equivalents which may be reasonably included within their scope.

I claim:

1. In a device of the class described, a T-square comprising a cross-piece having one straight edge and a convex portion on the other edge, an elongated translucent rule member secured at one end to said cross-piece and at right angles thereto, a depression in said cross-piece adjacent the end of said rule member, a second cross-piece of the same shape as said first cross-piece and pivotally secured thereto in spaced relation, a beveled edge on one longitudinal side of said rule member; a beveled edge on one side of the convex portion of each of said cross-pieces, a rod member threaded on one end and having a hook on the other end; said hook portion resting in said depression and said threaded portion projecting rearwardly from said cross-pieces, a channel bracket member mounted on said rod member; said channel edges being beveled and capable respectively of engaging the beveled edges respectively of said cross-pieces at times, and a control knob threaded on said rod and capable of engaging said bracket at times so that tightening of said knob will increase the frictional engagement between said bracket and said cross-pieces.

2. In a T-square, a pair of cross-pieces pivotally secured together; each of said cross-pieces having one straight edge and a convex portion on the opposite edge thereof; each of said convex portions having a beveled portion on one edge thereof, a bracket capable of engaging the beveled portions of said convex portions, means to support said bracket and a manually operable means of holding said bracket in engagement with said convex portions and releasing it therefrom.

3. In a T-square, a rule member, a pair of cross-pieces one of which is fixed and the other of which is rotatably secured to said rule member; said cross-pieces having a space between them and a well in one of them opening into the space, a rod extending into said space and bent to enter said well, a binding bracket slidably mounted on said rod and capable of engaging a portion of the respective edge portions of said cross-pieces and a means on said rod for forcibly moving said binding bracket into binding engagement simultaneously with both of said cross-pieces.

OSCAR ANTON OLSON.
